UNITED STATES PATENT OFFICE.

WILLIAM H. FAUBER, OF CHICAGO, ILLINOIS.

DESIGN FOR A SPROCKET-WHEEL FOR VELOCIPEDES.

SPECIFICATION forming part of Design No. 27,833, dated November 9, 1897.

Application filed September 18, 1897. Serial No. 652,200. Term of patent 3½ years.

To all whom it may concern:

Be it known that I, WILLIAM H. FAUBER, a citizen of the United States, residing in the city of Chicago, county of Cook, and State of Illinois, have invented and produced a new and original Design for Sprocket-Wheels for Velocipedes, of which the following is a specification, reference being had to the accompanying drawings, forming a part hereof.

10 In said drawings, Figure 1 is a view in side elevation of a sprocket-wheel made in accordance with my design. Fig. 2 is a sectional view taken on a direct line through the center of the wheel and through one of the spokes thereof.

15 A sprocket-wheel made in accordance with my design consists of an outer circular band or rim, an inner circular ring or hub concentric with said rim, and a plurality of spokes 20 or arms extending radially between said rim and hub and spaced at equal distances apart about said hub. Said rim is provided on its outer periphery with a plurality of openly-spaced radially - arranged projections or 25 sprocket-teeth. The central part of the wheel, embracing the spokes, the inner ring, and the inner part of the rim, is made of less thickness than the outer part of the rim, in which the teeth are formed, this reduction in thickness 30 of the inner part of the rim forming thereon an annular rabbet of a width approximately equal to one-half the radial width of the rim. Between the inner circumference of said ring, midway between each two adjacent spokes, are formed inwardly-projecting ornamental spurs or points, which are directed 35 inwardly a distance less than the width of the

rim and the margins of which are joined to the inner curve of the rim by short convex lines.

40 The spokes are five in number and are spaced at equal angular distances apart about the inner ring, from which they extend radially to the inner edge of the rim. Said spokes are widest at their parts a short distance outward from the inner ring and are tapered to their points of connection with the rim. The side edges of said spokes are slightly concave and are joined to the inner curved edge of the ring by short concave parts or fillets. Each spoke is provided on each side thereof, immediately adjacent to said inner ring and between the widest part of the spoke and said ring, with oppositely-arranged concave edges, which merge at their inner ends 55 into the curved outer periphery of the hub and form at the intersection of their outer ends with the side edges of the spoke oppositely - arranged laterally - directed salient points or angles, the said concave edges being 60 at a distance apart, at the points at which they approach nearest to each other, considerably less than the widest parts of the spoke or the distance between said points or angles.

65 The wheel is made of slightly concave or dished form, as shown in the sectional view.

I claim as my design—

A design for sprocket-wheels for velocipedes, substantially as shown and described.

WILLIAM H. FAUBER.
